COUPLER

Edmund P. Kinne and Frank H. Kayler, Alliance, Ohio, assignors to American Steel Foundries, Chicago, Ill., a corporation of New Jersey

Application September 7, 1928, Serial No. 304,415

9 Claims. (Cl. 213—69)

This invention pertains to draft rigging for railway rolling stock, and more particularly to that class of draft rigging especially designed for application to the underframes of railway cars, and includes in combination with car sills, means for connecting a coupler to the draft mechanism and for connecting the draft mechanism to the car underframe.

It is an object of this invention to provide in combination a vertical key connection adapted to permit relative movement between the yoke and the coupler, means for supporting and guiding at least one of the followers, and means for limiting the forward movement of one of said followers.

Another object is to obtain a strong and serviceable radial shank connection in the simplest possible manner, one which will have the least possible surfaces subject to wear, which result in slack in the connection; one in which radial (or angling) action of the coupler shank is provided for while maintaining equalized pull on the yoke jaws in tension, and full butt end contact area and equalized pressure on draft gear or follower under buffering stresses.

Another additional object is to provide a construction wherein the coupler shank permits of its being applied to cars having the accepted A. R. A. standard design for integral striking casting and coupler carrier, and wherein the angling of the coupler is limited only by the contact of shank sides against the sides of the coupler opening in the striking casting and not by contact with the yoke jaws, as in the present arrangement.

Yet another object is to provide a construction wherein the pivotal action between the coupler and yoke is provided for by the same piece which connects them for pulling action, that is, the vertical key, wherein, there are no superfluous connections with keys or small bearing pieces and wherein the vertical key is of ideal design to provide large bearing surface, free pivotal action and large area to resist shearing.

A further object is to provide a construction wherein generous bearing area is provided at key bearings and butt bearings, insuring minimum wear, and wherein large sectional areas in tension, compression and shear are also provided.

Still further object of the arrangement is to provide a construction in which the coupler angles freely regardless of the compression in the draft gear to thereby permit coupling on curves without delay or effort and in order to eliminate transmission of the side movement to the coupler

key to thereby avoid wear of the key and keyways and to prevent any blows on the cotter or other key fasteners.

Another further object is to provide a construction which is inexpensive to make and maintain and one which fulfills all requirements of manufacture and service, and which also is readily replaceable by parts of standard construction without material changes in the car or draft appliance.

Still further additional object is to provide coupler mechanism having a buffering piece separate from the coupler shank, permitting designing of the coupler structure to secure maximum strength in buffering areas to resist compressive stresses, and in such construction whereby recesses in the coupler butt used to cooperate with small attaching lips on a radial butt piece which may become broken off in service and result in the loss of the swivel, be eliminated, and to provide a coupler of such construction that if said coupler fails, it is only necessary to remove and replace the coupler proper.

Other objects, features, capabilities and advantages are comprehended by the invention, as will later appear and as are inherently possessed thereby.

Referring to the drawing:

Figure 1 is a longitudinal sectional top plan view of a draft appliance made in accordance with the invention, the same being shown in operative position with respect to the draft sills;

Figure 2 is a longitudinal sectional view in elevation of the draft appliance shown in Figure 1 of the drawing; and

Figure 3 is a longitudinal fragmentary view in cross-section taken in the plane represented by line 3—3 of Figure 1 of the drawing.

Referring now more in particular to the drawing, an embodiment selected to illustrate the invention includes draft sills 20 of any form, such as I-beam or channel section, which are spaced apart or have secured thereto a suitable number of straps or carry irons 21. The forward ends of the sills are secured to a striking casting 22, as by rivets 23, which may be secured as at 24 to end sills 25 and floor 26, the said striking casting being preferably provided with a bearing 27 for supporting the coupler shank 28 of the coupler member 29. The striking casting 22 may conveniently be of such form as to extend inwardly of the sills and having members to provide stops 30 at the after ends of said casting.

The striking casting also has a return portion 31. 55

providing a stop 32 limiting forward movement of the yoke.

Back stop casting 33 may be provided between the draft sills 20 and secured thereto as by rivets 34, the same being preferably attached adjacent the cross bearers or bolsters 35. The back stop casting may conveniently be of such form as to have a portion extending toward the striking casting and provided with stops 36. A yoke 37 is provided which is of the vertical plane type, said yoke being provided with the usual draft gear disposed between the front and rear followers 38 and 39 respectively. This yoke is provided with forward ends or jaws 40 having flattened portions 41 and 42 adapted to provide a generous bearing area against the stop 32 and at the rear of the lower portion of the striking casting adjacent the bearing 27.

The yoke 37 at the forward end of the jaws is provided with vertically disposed straps 43 so disposed, however, that they in no way impede the angling movement of the coupler 29. The yoke is provided at its forward end with elongated vertically disposed apertures or keyways 44 adapted to accommodate a vertical key 45, a cage or housing 46 depending below the yoke being provided adjacent the lower keyway 44 for retaining the vertical key 45 in operative position. This housing is formed with facing flanges 47 and 48 adapted to support a key retaining locking plate 49 adapted to be inserted through the aperture between the flanges and locked in place on said flanges by means of the removable key 50.

Disposed between the coupler shank and the follower 38 is a separate buffing piece 75 which is provided with a flat rear face adapted to have abutting contact with the front follower and provided with an arcuate forward face 76 adapted to have cooperative engagement with a complementary arcuate face 53 at the end of the coupler shank. It will be noted that the buffing piece is designed without attachment to the coupler and is merely positioned between the upper and lower members of the yoke and provided with forwardly extending spaced guides 77 to maintain it in proper operative position with respect to the coupler butt. Under normal conditions of operation, that is, when the coupler is under neither compression nor tension stresses, the arcuate forward face 76 contacts the coupler butt and the rear flat surface contacts the front follower 38.

The guides 77 upon the upper and lower sides of the buffing piece position it between the yoke members, the guides extending forward and lying on the free side of the central portion of the shank. Under buffing action, the piece moves rearward with the coupler butt and follower, or draft gear, the stresses being transmitted to the side sill through the rear follower 39 or rear of draft gear, and stops 36, it being noticed that a maximum bearing area is provided between the coupler shank and draft gear through the buffing piece. In this position, the guides 77 extend on either side of the shank though they are so positioned that angling of the coupler may readily take place. In draft, the coupler moves forward and away from the follower and pulls the yoke forward to transmit the stresses to the draft sills through the front follower 38, or front of draft gear, and the stops 30, all as has been particularly described.

The buffing piece is maintained within the yoke and supported by the lower member of the yoke and is free to move forward with the yoke and maintains substantially the same position

with respect to the coupler yoke and butt as in normal position. Should, however, the draft gear be subjected to a sudden forward jerk, the buffing piece may remain in close proximity to the follower or draft gear instead of moving forward as a unit with the coupler shank, it being maintained in position by cooperation of the guides 77 with the yoke portion 78, it being further guarded against misplacement by the fact that it is closely positioned between the stops 30, and this guiding action of the buffing piece is true for any intermediate position which it may assume between the extreme positions of buffing and draft.

While we have herein described and upon the drawing shown an illustrative embodiment of the invention, it is to be understood that the invention is not limited thereto but may comprehend other constructions, arrangements of parts, details and features without departing from the spirit of the invention.

We claim:

1. In a draft appliance, the combination of a vertical plane yoke having upper and lower straps, a draft gear carried by said yoke, a coupler mounted in said yoke, said straps having shoulders spaced rearwardly of the forward end thereof, and means interposed between said gear and coupler and provided with forwardly disposed guide arms engaging said shoulders whereby the same is maintained in operative position.

2. In a draft appliance, the combination of a vertical plane yoke having upper and lower straps, a draft gear carried by said yoke, a coupler mounted in said yoke, said straps being provided with shoulder portions in spaced relation to the ends thereof, and means between said gear and coupler adapted to provide bearing surface for said coupler, said means having parts embracing said shoulder portions whereby the same is maintained in operative position.

3. In a draft appliance, the combination of a yoke, a draft gear carried by said yoke, a coupler mounted in said yoke, said yoke having a thickened head portion to provide inwardly extending portions having shoulders in spaced relation to the sides thereof, and means between said gear and coupler adapted to provide bearing surface for said coupler, said means having parts engaging said shoulder portions whereby the same is maintained in operative position.

4. In a draft appliance, the combination of a yoke, a draft gear carried by said yoke, a coupler mounted in said yoke, said yoke having straps provided with oppositely disposed shoulder portions, and means interposed between said draft gear and coupler adapted to provide bearing surface for said coupler, said means having pairs of spaced arms disposed to engage said shoulder portions to prevent lateral displacement thereof whereby the same is maintained in operative position.

5. In a draft appliance, the combination of a yoke, a draft gear carried by said yoke, a coupler mounted in said yoke, said yoke having a hooded head provided with oppositely disposed shoulder portions, and means interposed between said draft gear and coupler adapted to provide bearing surface for said coupler, said means having spaced pairs of forwardly extending guide arms adapted to engage said shoulder portions to prevent lateral displacement thereof whereby the same is maintained in operative position.

6. In a draft appliance, the combination of a yoke, a draft gear carried by said yoke, a cou-

pler mounted in said yoke, said yoke having a hooded head having upper and lower walls provided with inwardly disposed portions having shoulder portions, and means interposed between said draft gear and coupler adapted to provide bearing surface for said coupler, said means having pairs of upper and lower forwardly extending guide arms adapted to engage said shoulder portions to prevent lateral displacement thereof whereby the same is maintained in operative position.

7. In a draft appliance, the combination of spaced sills, stops on said sills, and draft means operatively carried by said sills and cooperating with said stops, said means including a vertical plane yoke disposed between said sills and provided with spaced shoulder portions, a follower cooperating with said yoke and extending laterally for engagement with said stops, a coupler movably connected to said yoke, and coupler cooperating means normally disposed between said stops, said coupler cooperating means having parts engaging said shoulder portions to prevent lateral displacement thereof.

8. In a draft appliance, the combination of spaced sills, stops on said sills, and draft means operatively carried by said sills and cooperating with said stops, said means including a vertical

plane yoke disposed between said sills and provided with spaced shoulder portions, a follower cooperating with said yoke and stops, a coupler having an arcuate bearing portion adjacent said follower, a vertical pin loosely pivoting said coupler to said yoke, and means between said follower and coupler and cooperating with said arcuate bearing portion to provide for substantially constant bearing between said coupler and follower irrespective of the horizontal angling of said coupler, said means being normally disposed between said stops, said coupler cooperating means having parts engaging said shoulder portions to prevent lateral displacement thereof.

9. In a draft appliance, the combination of a yoke, a draft gear carried by said yoke, a coupler connected to said yoke, said yoke having oppositely disposed straps and connecting straps therebetween adjacent their forward end, said yoke having shoulder portions rearwardly of said connecting straps, and means between said gear and coupler adapted to provide a bearing surface for said coupler, said means embracing said shoulders for maintaining the same in operative position.
